UNITED STATES PATENT OFFICE.

EMIL FOX, OF NEW YORK, N. Y., ASSIGNOR TO WM. MANNHEIM & CO., OF SAME PLACE.

DESIGN FOR A BOX-LOOP FOR HARNESS.

SPECIFICATION forming part of Design No. 20,720, dated May 12, 1891.

Application filed March 20, 1891. Serial No. 385,825. Term of patent 14 years.

To all whom it may concern:

Be it known that I, EMIL FOX, of the city, county, and State of New York, a citizen of the United States, have invented and produced a new and original Design for Box-Loops for Harness, of which the following is a specification.

This invention relates to a design for a box-loop for harness; and it consists of embossed longitudinal bands or stripes and transverse bars that intertwine with the longitudinal stripes, they all being inclosed by a plain embossed border.

The nature of my design is clearly shown in the accompanying drawing, in which a face view of the box-loop is shown and to which reference is made.

A in the drawing represents a box-loop, the face of which is ornamented by means of longitudinal stripes *a*, which interlock with transverse stripes *b*, of less width, so as to produce

an effect in the nature of wicker-work. Along the edges of the face are arranged longitudinal and transverse raised lines to form a border *d* for the face of the box-loop. 25

Having thus described my invention, I claim as new and desire to secure by Letters Patent—

A design for the surface of a box-loop for harness, consisting of longitudinal stripes, and 30 transverse intertwining parts of less width than the longitudinal stripes, and an oblong border of raised lines, substantially as set forth.

In testimony that I claim the foregoing as my invention I have signed my name in presence of two subscribing witnesses. 35

EMIL FOX.
